UNITED STATES PATENT OFFICE

STEPHEN D. BAKER, OF NEW YORK, N. Y.

DESIGN FOR A GRAB RAIL OR SIMILAR ARTICLE

Application filed October 19, 1931. Serial No. 41,444. Term of patent 3½ years.

To all whom it may concern:

Be it known that I, STEPHEN D. BAKER, a citizen of the United States, and a resident of New York, in the county of New York and State of New York, have invented a new, original, and ornamental Design for a Grab Rail or Similar Article, of which the following is a specification, reference being had to the accompanying drawings, forming part thereof.

In the drawings:

Fig. 1 is a top plan view,

Fig. 2 is a front view,

Fig. 3 a side view, and

Fig. 4 a section on the line 4—4 of Fig. 1 of a grab rail embodying my new design.

I claim:

The ornamental design for a grab rail or similar article, as shown.

STEPHEN D. BAKER.
